UNITED STATES PATENT OFFICE.

OTTO BUTZBACH, OF CHICAGO, ILLINOIS.

LAUNDRY DRIER.

Application filed September 24, 1924. Serial No. 739,736.

To all whom it may concern:

Be it known that I, OTTO BUTZBACH, a citizen of the United States, residing at Chicago, in the county of Cook and State of Illinois, have invented certain new and useful Improvements in Laundry Driers, of which the following is a specification.

The invention relates to improvements in laundry driers.

10 The invention is shown incorporated in a drier of the tumbler type.

One object of the invention is to improve the system of circulating dry warmed air thru the clothes containing cylinder.

15 Another object is to produce uniform moisture interchange throughout the cylinder.

Another object is to dry the clothes by subjecting them to sub-atmospheric pressure.

20 Another object is to provide means for introducing individual streams of air under the clothes contained in the cylinder while they are falling from a higher to a lower 25 elevation.

Another object is to change the direction of the relatively dry air thru the cylinder, periodically, in timed relation with the rotation of the cylinder.

30 Another object is to provide a drier so arranged that lint from the drying fabric cannot fall out of the cylinder but is caught by the draft of air and thereby removed from the cylinder thru the exhaust opening 35 of the suction fan.

Another object is to provide a cylinder having openings or perforations thru which warm air enters, the perforated portions thereof being free from contact with the 40 batch of fabric or clothing being dried therein, so that the entrance of air is not restricted by the closure of some of the perforations, and buttons and other attachments on the garments therein are not torn 45 off.

Another object is to provide a cylinder with a circumferential wall divided into imperforate separated sections, said sections being bridged by internal hollow ribs, each 50 of said ribs having an imperforate leading

leg and a perforate trailing leg with respect to direction of rotation.

Other objects, advantages and benefits will hereinafter appear from a consideration of the following description when taken 55 with the drawings wherein:

Figure 1 is a side elevation of the machine showing parts in section.

Fig. 2 is a transverse section taken on line 2-2 of Fig. 1.

Fig. 3 is a horizontal section thru the timing mechanism taken on line 3-3 of Fig. 4.

Fig. 4 is a section taken on line 4-4 of Fig. 3.

Fig. 5 is a longitudinal section taken on line 5-5 of Fig. 8.

Fig. 6 is an enlarged sectional view of the air heating chamber and steam pipes therein, shown in less detail in Fig. 2.

Fig. 7 is an enlarged fragmentary section taken on line 7-7 of Fig. 2.

Fig. 8 is an end elevation of the drier.

Fig. 9 is a side elevation showing part in section of the driving mechanism of the 75 machine.

Fig. 10 is a plan view thereof.

Fig. 11 is an end elevation.

Fig. 12 is a broken away elevation of the motion changing cam shown in Figs. 3 80 and 4.

Fig. 13 is a section on line 13-13 of Fig. 9.

Fig. 14 is a section taken on line 14-14 of Fig. 9.

In all the views the same reference characters indicate similar parts.

The character of cylinder adapted for carrying the invention into effect and which forms the subject matter of some of the 90 claims will first be specifically described and the method of operation will then be pointed out.

The cylinder 15 is preferably divided into a plurality of compartments 16-17-18 and 95 19 within which to contain separate batches of clothes when the device is to be used for laundry purposes. These compartments are separated by recticular partitions 20, made preferably of wire cloth. The open ends of 100

the cylinder are provided with similar partition walls 20, as more clearly shown in Fig. 1. Both ends of the cylinder are supported by open spoke spiders 21 from which 5 extends a gudgeon shaft 22, on the left side viewing Fig. 1, and which is supported in a bearing box 23 on the frame member 24. The frame member 25 supports the other end 10 of the cylinder and carries the mechanism for rotating the cylinder. From this power end of the cylinder a shaft 26 has bearings in the box 27. The shaft 26 and the cylinder 15 carried thereby, is driven by a gear wheel 28 and the latter is driven by a pinion 29 15 from the power shaft 30. A more detailed description of the driving and controlling mechanism will hereinafter follow.

The cylinder's circumferential wall is divided into a plurality of spaced, imperforate 20 arcuate sections 31. One of these sections is hinged at 32 to provide a door which may be held closed by the latch 33. This door section may be divided into a plurality of doors, one for each compartment, 16-19 25 inclusive or each door may be made to close two or more compartments.

The cylinder is rotatable in a closed air casing 34 which is mounted on and in open communication with an air heating casing 35.

The arcuate sections 31 are bridged by internally extending hollow ribs which are substantially coextensive with the effective longitudinal dimensions of the cylinder. 30 These ribs are securely riveted or otherwise joined to adjacent edges of sections 31 as at 31', and constitute one means for holding them together.

It is important to note that only one wall 40 or leg of each of the ribs 36 is perforated. For example, if the cylinder is to be rotated clockwise, as shown by the arrow 37 of Fig. 2, then, in that event, the trailing wall or leg 38 should be perforated, as more clearly 45 shown in Fig. 1, and the leading leg 39 is imperforate. In any event the wall of the rib upon which the clothes rest when they are being lifted is the imperforate wall. With such an arrangement the perforations 50 in the ribs cannot be closed by contact with the clothes under any condition of operation and, furthermore, under no condition of operation can lint from the drying clothes fall out of the cylinder into the air heating chamber 35' therebelow, nor can buttons or other attachments on the garments be caught in the perforations and pulled off. A partition wall 40 overlies the air heating units 41 in casing 35, of which there 55 are a plurality and each unit is separately removable from the casing. The partition has a transverse opening 42 which is about equal in width to the spread of the legs of the ribs between adjacent arcuate sections 60 31 of the cylinder.

Dried air is drawn from the heating chamber 35' of the casing 35 thru the opening 42 into the interior of the ribs, and thru the openings in the wall 38 of the ribs into the cylinder 15.

The casing 34 has extending axially from each of its ends a hollow air receiving header 43-43', and a lateral extension 44. One extension 44 connects the interior of the cylinder 15 with an air conduit 45 and the other 70 extension 44 is connected to air conduit 46. These conduits, 45 and 46, are connected to a valve chamber 47. In the valve chamber there is contained an oscillatable butterfly valve 48, secured to a crank shaft 49 by 75 means of which the valve is moved on its axis.

An exhaust fan 50, driven by any suitable means, as by a belt about the pulley 51, is the means for drawing the moisture laden 80 air from the cylinder and fresh air into the air drying chamber. The air intake of the fan is connected by a conduit 52 to the valve chamber 47. The exhaust or discharge 85 openings 53 of the fan may be connected to a conduit to lead the discharged air to any desired locality.

When the valve 48 is in position shown in Fig. 5, the air from the cylinder 15 will pass thru the header 43, extension 44, thru 90 conduit 46, into valve chamber 47 and thru conduit 52 into the fan from which it will be discharged thru the opening 53. When the valve is moved thru an arc about 90 degrees, the conduit 46 will be closed and conduit 45 opened, whereupon the direction of air thru the cylinder will be reversed.

The valve 48 is oscillated in timed relation with the rotation of the cylinder to accomplish this result, by a timing mechanism 54 105 and the connecting rod 55 to be hereinafter more particularly described.

Mounted on the frame members 24 and 25, and connected at its ends thereto by straps 56 is a pipe 57 which is used to tie the frame members together and is utilized to support bearing pedestals 58 for the power shaft 30.

The timing mechanism 54 is also supported on the pipe 57 by clamping plates 59.

The shaft is provided also with bearing supports 60 on the upper ends of the frame members 24 and 25. The power shaft 30 also carries tight and loose pulleys 62 and 61, respectively, which are to be driven, selectively by a bolt 63 shiftable from one to the other by the belt shifter 64. The belt is shown as on the loose pulley 62. The belt shifting device consists of the slidable shaft 65 mounted on the bracket 66 which is secured to the frame member 25. Belt-guiding fingers 67 are secured to the slidable shaft 65 and overlie the belt 63 to shift it alternatively between the pulleys 61 and 62.

A bell crank lever 68 is pivoted on the 130

bracket 66 at 69, its upper arm 70 is slotted at 71 and is bifurcated to straddle the shaft

65. A pin 72 passes thru the shaft and into the slot 71. Rocking the bell crank lever 5 68 reciprocates the shaft 65 to shift the belt.

The arm 73 of the bell crank lever 68 is connected by a link 74 to another bell crank lever 75 at 76. The arm 77 of this lever is 10 connected by a link 78 to a hand lever 79 which is secured to a short reciprocatable shaft 80 and which moves axially therewith. It is now manifest that when the hand lever 79 is moved into position shown in Fig. 11, 15 the belt will be moved from the driving pulley 61 to the loose pulley 62. Before the belt can be shifted, as described, the shaft 80, pinion 81, crank 82, lever 79 and the angle plate 83 must be moved laterally to 20 dotted line position, shown in Fig. 9. This cannot be done until the angle plate 83 which is fixed to shaft 80, has been moved outwardly to clear the fixed angle plate 84 at which time geared pinion 81 is moved, 25 so that it is out of mesh with the cylinder driving gear wheel 28.

When the lever 79 is thus moved to shift the belt from the loose to the driving pulley an integral lip 85 is rotated with the handle 30 and acts as a stop against the angle plate 84 so that the shaft 80 cannot be moved axially back to its idle position until the handle 79 has been moved back to idle position, as shown in Fig. 11 when the driving belt 63 will again be shifted to the idle or loose pulley.

When shaft 80 has been moved into either of its described positions, it may be clamped and held in said position by the slidable 40 clamping bolt 86. The outer end of bolt 86 is threaded in the hub of the handle 87. The bolt is cut away at 88, to permit the rod 80 to slide freely and when the rod is in selected position the handle 87 is turned to 45 draw the bolt outwardly to clamp and hold the rod.

When the pinion 81 is in mesh with gear wheel 28, rotation of the handle 82 will rotate the cylinder 15 until door 31' in a side- 50 wall thereof is brought into position shown in Fig. 2, to register with the door 90, in the casing 34, and which is hinged at 91. A latch 92 holds the door 90 closed and the counterweights 93 hold it open. These 55 weights are connected to cables 94 which pass over pulleys 95 supported on shaft 96 which is supported on standards 97 fixed to the pipe 57.

It is, of course, obvious that the cylinder 60 15 may not be rotated by the handle 82 while the driving belt 63 is on the driving pulley 61 and it is, furthermore, manifest, from the foregoing description, that the belt may not be shifted to the driving 65 pulley from the idle pulley until the pinion

81 has been moved to an idle position out of mesh with gear wheel 28.

It is, therefore, impossible to rotate the cylinder 15 by power while its door 31' stands in open position.

In the chamber 35' enclosed by the casting 35 the air drying and heating units 41 are contained. These units are self contained and may separately be introduced into said chamber and independently removed therefrom.

Each unit comprises a header 100 to which a steam inlet pipe 101 is connected and another header 102, to which a steam exhaust pipe 103 is connected.

A plurality of pipes 104 are connected in the header 100 and these pipes are surrounded by pipes 105 respectively. The pipes 105 are closed at their outer ends and, therefore, steam, hot water or other liquid, heating agent will flow thru the pipes and headers as shown by the arrows in Fig. 6.

The doors 106, one on each side of the casting 35 are removable and are held closed by buttons 107.

The casing 35 has foraminous doors 108 thru which cold air enters to be heated and dried by the heating units 41 within the casing.

The valve 48 in the valve chamber 47, is 95 oscillated periodically in timed relation with the rotation of the cylinder 15 by the timing device 54, to change the direction of air passing thru the cylinder.

The timing device shown and which is 100 capable of carrying into effect this feature of the invention consists of a casing 110 thru which the power shaft 30 passes. A mitre gear 111 is secured to said shaft and is in mesh with a mitre gear 112, the latter is secured to shaft 113. To this shaft is secured a gear pinion 114 in mesh with a gear wheel 115 loose on a parallel shaft 116. To the gear wheel 115 is secured a gear pinion 117 which is also loose on shaft 116. The pinion 117 is in mesh with gear wheel 118 which is loose on shaft 113.

Secured to gear wheel 118 is a disk 119 which is blind except for about eight teeth 120 included between lines 121 and 122.

Extending laterally from the disk 119 is a locking ring 125 having a gap 124 spanning the teeth 120.

A gear pinion 125 is secured to shaft 116 by a key 126. A shield 127 extends over the teeth of pinion 125 except as it is cut away on opposite sides, as at 128. The gap provided with the cut away part cooperates with the ring 123 to hold the shaft 116 stationary until the teeth 120, in disk 119, engage the exposed teeth of the pinion 125 at which time the part 129 of the shield 127 will pass into the gap 124 made in the ring 123, thus permitting the shaft 116 to be rotated one half of a revolution. During the 130

remainder of the revolution of the disk 119 the ring 123 with its engagement with shield 127 will hold the shaft 116 from being rotated in a manner similar to a Geneva movement.

Secured to the shaft 116 is a crank arm 131 which operates valve 48 by the connecting link 55 and the crank 130.

By this means the direction of air thru 10 the cylinder is changed in regular periods in timed relation with the rotation of the cylinder 15.

In Fig. 2 an outline of the batch of clothes is shown at 132, and it will be observed 15 that when the cylinder is rotated clockwise that the perforations in the ribs 39 are never covered by the clothes. On the contrary they are left open and air is thereby introduced under the clothes.

20 To prevent air from entering space 113 in the upper part of the casing 34, drag plates 134 extend longitudinally of the cylinder and bear upon segments 31. Rods 134 pass thru the ribs 36 and thru rings 20' 25 which bear the reticular part 20 to provide the perforate partitions. The ribs may be transversely slotted at their apices to permit the rings 20' to enter.

One object for changing direction of 30 travel of air thru the cylinder 15 is to more uniformly dry the contents.

Having described my invention what I claim is—

1. A laundry drier having a rotatable cylinder comprising a series of longitudinally extending, circumferentially-spaced, imperforate segments and internally located hollow perforate ribs connecting said segments.

2. A laundry drier having a rotatable cylinder comprising a series of longitudinally-extending, circumferentially-spaced, imperforate segments and internally-located, hollow ribs connecting said segments, each rib having perforations in one wall only and said perforate walls all facing in one circumferential direction uniformly throughout the structure.

3. A laundry drier having a rotatable cylinder comprising a series of longitudinally-extending circumferentially-spaced, imperforate segments; internally-located hollow ribs, each rib having one perforate and one imperforate wall and uniformly arranged, and a plurality of perforate partitions in said cylinder dividing it into a plurality of compartments all of which are open thru the perforations in said ribs.

4. A laundry drier having a rotatable cylinder open at both ends and comprising a plurality of longitudinally extending, circumferentially-spaced, imperforate segments; a plurality of hollow, internally-located ribs, each rib connecting the side edges of adjacent segments and each rib having one perforate and one imperforate wall ar-

ranged symmetrically about the cylinder; perforate partitions dividing said cylinder into compartments venting thru said ribs, and means to cause air to pass thru said ribs, cylinder and perforated partitions.

5. A laundry drier having a rotatable cylinder open at both ends and having a peripheral wall divided into circumferentially spaced imperforate segments; hollow V-shape ribs having one perforate and one imperforate wall located within the cylinder and connected to the longitudinal edges of adjacent segments; perforate partitions dividing the cylinder into compartments and rods extending thru said ribs and said partitions to hold the parts together.

6. A laundry drier comprising a rotatable cylinder having a plurality of spaced imperforate peripheral segments; hollow internal ribs, each rib having one perforate and one imperforate wall connected to the longitudinal edges of adjacent segments, symmetrically arranged throughout; a casing into which the ends of said cylinder extend; a casing containing air heating elements, said casing open to said ribs and means to cause air to flow from one casing to the other thru said cylinder.

7. A laundry drier having a rotatable cylinder open at both ends and having a peripheral wall divided into circumferentially spaced imperforate segments; hollow V-shape ribs having one perforate and one imperforate wall located within the cylinder and connected to the longitudinal edges of adjacent segments; perforate partitions dividing the cylinder into compartments and rods extending thru said ribs, means to cause air to flow from one casing to the other thru said cylinder in a given direction and means to periodically change the direction of air flow thru said cylinder.

8. A laundry drier comprising a rotatable cylinder open at both ends and having internal longitudinally extending perforate ribs thru which air passes; means to drive the cylinder; means to exhaust the cylinder alternately from said ends and means operable by said driving means to periodically change direction of air thru said cylinder.

9. A laundry drier comprising a rotatable cylinder open at both ends, and having openings thru the periphery to admit air; a casing containing air-drying means communicating with said openings; an air receiving header at each end in communication with the interior of said cylinder at its respective ends; a valve casing containing an oscillatable valve; an exhaust fan connected to said valve casing; a conduit connecting said valve casing to the respective headers, one for each, and means operable by the cylinder-driving means to periodically oscillate said valve to change direction of flow of air thru said cylinder.

10. A laundry drier comprising a cylinder having a door in its peripheral wall; a casing in which the cylinder is contained having a door in one of its side walls; power driving means to rotate the cylinder; hand driving means to rotate the cylinder to bring said doors into register and means to lock the power driving means from use when said hand driving means is in operative position.

11. A laundry drier comprising a rotatable cylinder having open ends and longitudinal openings; a casing extending longitudinally of the cylinder having an opening in its longitudinal upper wall near its mid-portion and having substantially open ends; a plurality of independently separable air-drying units in said casing, and means to draw air thru said casing and alternatively thru the respective ends of said cylinder.

In testimony whereof I hereunto set my hand.

OTTO BUTZBACH.
